UNITED STATES PATENT OFFICE.

WILLIAM H. STEVENS, OF NEW YORK, N. Y.

SUSPENDERS.

1,365,862.

Specification of Letters Patent. Patented Jan. 18, 1921.

Original application filed September 26, 1918, Serial No. 255,784. Divided and this application filed November 10, 1919. Serial No. 337,066.

To all whom it may concern:

Be it known that I, WILLIAM H. STEVENS, a subject of the King of Great Britain, residing at New York, in the county of New York and State of New York, have invented certain new and useful Improvements in Suspenders, of which the following is a specification.

The present application is in substance a 10 division from my application Serial No. 255,784.

The principal object of this invention, as in the application referred to, is to provide a construction of suspenders in which the 15 back strap, which is to be secured to two buttons at the back of the waistband of the trousers, as usual, is a single length of preferably elastic fabric threaded through a connecting member of such construction and 20 in such manner that the fabric is held substantially immovable in the connecting member under ordinary conditions of use, though it may be readily adjusted therein when desired; and to provide further for making 25 the shoulder strap part of the suspenders of a single piece of fabric threaded through the same connecting member in such manner that it will be readily slideable therein to 30 allow for various bending movements of the wearer in use.

Other objects and aims of the invention, more or less broad than those stated above, together with the advantages inherent, will be in part obvious and in part specifically 35 referred to in the course of the following description of the elements, combinations, arrangements of parts, and applications of principles constituting the invention; and the scope of protection contemplated will 40 appear from the claims.

In the accompanying drawing, which is to be taken as part of this specification, and in which I have shown a merely preferred form of embodiment of the invention, Figure 1 is an elevation of a pair of suspenders embodying my invention; Fig. 2 is an enlarged view in elevation illustrating the connecting member, with the back strap and shoulder strap parts threaded through it, looking at one side of the connecting member; Fig. 3 is a similar view looking at the other side of the connecting member; Fig. 4 is a plan view of the form of connecting member; Fig. 5 is a sectional view taken on

the line 5—5 of Fig. 2; Fig. 6 is a sectional view taken on the line 6—6 of Fig. 2.

Referring to the numerals on the drawings, 11 indicates the back strap of a pair of suspenders, comprising a single length of preferably elastic fabric, having its ends 55 formed with button-holes 12. This back strap is threaded through a connecting member 14 shown in detail in Fig. 4. This connecting member comprises a flat frame of suitable material, as for instance metal or 60 celluloid, provided at the top with two parallel slots 15 and 16, defining a cross-bar 17 between them, while 18 indicates a cross-bar 65 which constitutes the upper end of the frame, defined on one side by the upper slot 70 15. Below the slots 15 and 16 I provide in the frame a pair of slots 19 and 20, which diverge from the bottom of the frame toward the top.

The back strap is threaded through this 75 frame as shown in Figs. 1, 2 and 3. Referring to Fig. 2, in which the parts are shown as they will appear when on the person, the back strap 11 is threaded through the slot 19 from the inner face of the connecting member, thence over the outer face of the connecting member, thence through the upper slot 15 from the outer face of the connecting member, thence over the inner face of the cross-bar 17 of the connecting member, 80 thence from the inner face of the connecting member through the slot 16 to the outer face of the connecting member, and thence over the outer face of the connecting member but under the course 21 of the fabric and 85 from the outer face of the connecting member through the second diverging slot 20 to the inner face of the connecting member. The result of this threading of the fabric, 90 because of the inherent resiliency of the material of which the connecting member is made, which is enhanced by the manner in which it is slotted, is that when once the back strap is placed in position as shown in 95 Figs. 1, 2 and 3, it is substantially fixed in the connecting member under ordinary strains of use, it being understood of course that the various slots will be of a width proportioned to the thickness of the fabric so 100 that when the fabric is threaded through the slots it will not be readily slideable therein. The upper slot 15 of the frame is however made somewhat wider than the parallel 105

slot 16 because it is intended to accommodate the shoulder strap portion 22 of the suspenders preferably a single length of non-elastic fabric, which slides readily back and forth through the slot 15 in accordance with the varying movements of the shoulders of the wearer. This shoulder strap portion is provided with the usual adjusting buckles 24 in which the ends 25 of the strap 10 may be adjusted for length, and in the loops of the strap ends formed between the adjusting buckles 24 and the ends of the strap 22 are secured the usual fitments 26, through which may be threaded the double-ended straps 27 for attachment for buttons at the front of the trousers, all as shown in Fig. 1. The result of this construction is that the back strap provides the necessary stretch and give to the article though the back strap 15 is itself immovably held in the connecting member; while the shoulder strap portion is readily slideable through the connecting member, allowing for movements of the shoulders of the wearer. The movements of 20 the shoulder strap may be facilitated and wearing or chafing at the point where it slides beneath the bar 18, be prevented by curling over the lower edge of this bar, as indicated at 28 to form a widened and 25 rounded bearing edge.

Inasmuch as many changes could be made in the above construction, and many apparently widely different embodiments of my invention could be made without departing 35 from the scope thereof, it is intended that all matter contained in the above description or shown in the accompanying drawing shall be interpreted as illustrative and not in a limiting sense.

40 It is also to be understood that the language used in the following claims is intended to cover all the generic and specific features of the invention herein described and all statements of the scope of the invention, which, as a matter of language, might be said to fall therebetween.

I claim:—

45 1. Suspenders comprising a connecting member of flat material having two parallel slots at the upper end and two slots at the

lower end diverging toward the upper end, a back strap made of a single length of material threaded through one of the diverging slots and over one face of the connecting member through the uppermost slot, over the 55 opposite face of the connecting member, through the second parallel slot and thence through the second diverging slot, and a shoulder strap portion slideable in the uppermost parallel slot.

60 2. Suspenders comprising a substantially flat connecting member having two substantially parallel horizontal slots at the upper end thereof providing two substantially horizontal bars at such upper end and two upwardly diverging slots below said bars, a back strap passed through said diverging slots and engaged over the lower bar and a shoulder strap engaged with the upper bar, the upper substantially horizontal slot being of greater width than the lower one to admit both the back strap and the shoulder strap.

65 3. Suspenders comprising a substantially flat connecting member having two substantially parallel horizontal slots at the upper end thereof providing two substantially horizontal bars at such upper end and two upwardly diverging slots below said bars, a back strap passed through said diverging 70 slots and engaged over the lower bar and a shoulder strap engaged with the upper bar, the material at the edge of the upper substantially horizontal slot being curled over to form a rounded bearing surface for the 75 strap engaged therewith.

80 4. Suspenders comprising a substantially flat connecting member having two substantially parallel horizontal slots at the upper end thereof providing two substantially horizontal bars at such upper end and two upwardly diverging slots below said bars, a back strap passed through said diverging 85 slots and engaged over the lower bar and a shoulder strap engaged with the upper bar, the material at the edge of one of the slots being curled over to form a rounded bearing.

90 In testimony whereof I affix my signature.
WILLIAM H. STEVENS.
